INVENTOR.

JOHN G. HARROLD.

BY

D. Anthony Usina

ATTORNEY.

UNITED STATES PATENT OFFICE.

JOHN G. HARROLD, OF QUINCY, MASSACHUSETTS.

PNEUMATIC SIGNAL APPARATUS.

Application filed April 14, 1922. Serial No. 552,625.

To all whom it may concern:

Be it known that I, JOHN G. HARROLD, a citizen of the United States, and resident of Quincy, Massachusetts, have invented 60
5 certain new and useful Improvements in Pneumatic Signal Apparatus, of which the following is a specification.

This invention relates to improved apparatus whereby signals may be transmitted 10 from a remote point. The apparatus while applicable to many uses is particularly designed for use in connection with a rivet delivery apparatus such as described in my co-pending application Ser. No. 505,734, 15 filed October 6, 1921.

The delivery apparatus is adapted for feeding rivets from a sending station, for example, in proximity to a heating forge to one or more receiving stations located at remote points where the rivet work is to be done. It is often desirable to have the heating forge and the sending station in such a location that it is out of the range of the vision or hearing of the operators at the receiving stations. It is, therefore, advantageous to provide a signal located in juxtaposition to the sending station whereby the workmen at the remote receiving stations can signal the sending operator. To these 25 ends I have provided a pneumatically actuated signal which is connected by suitable flexible tubing to valves adapted to be operated by the workmen at the receiving station or stations.

30 The invention is illustrated in the accompanying drawings in which Fig. 1 is a somewhat diagrammatic view, showing the general arrangement of an apparatus consisting of a sending station including two delivery units and two receiving stations located at remote points;

Fig. 2 is an enlarged view of one form of signal and the valve for controlling the same;

45 Fig. 3 is a view of a modified form of signal;

Fig. 4 is a detail of a vent valve such as located at the receiving stations;

Fig. 5 is a side view of one of the delivery units;

Fig. 6 is a section on line 6—6 thereof.

Referring first to Fig. 1, A is a sending station at which are located a plurality of delivery units 10. There are two such units

55 shown in the drawing but it is understood that in practice there will often be many

more so that a single operator can feed rivets to a great number of locations, for example, at different points on a ship or at different points where riveting operations are being carried on in a steel building. B and C represent receiving stations to which the rivets or other articles are fed. S is a signal which is located in juxtaposition to the delivery units 10 at the sending station 65 A. Valves V and V¹ are located at the receiving station B and C and are connected by flexible pipes P and P¹ through a branch P² which in turn is connected by a pipe P³ to the signal S. 70

The arrangement is such that when either of the valves V and V¹ are actuated, they vent air in the pipes P and P¹ and by means hereinafter described cause the signal S to be operated. The signal S may be of any 75 desired character. Audible signals in the form of a whistle and a bell are herein shown, although it is to be understood that if desirable a visual or other type of signal may be employed. 80

The delivery apparatus can be of any suitable type but is preferably of the form shown in the co-pending application above referred to wherein the rivets are introduced to a hopper-like receptacle 10 having 85 a hook 11 thereon which is adapted to engage a bar 12 or any suitable fixed support such as an edge of the heating forge. The rivets to be conveyed pass through a delivery pipe 13 the internal diameter of 90 which is slightly greater than the head of the rivet 14. The top of the receptacle is formed with an opening 16 adapted to be closed from the inside by a door 17 hinged at 18. This door is adapted to normally 95 hang down as in Fig. 5 when there is no pressure in the receptacle and it easily swings shut when the pressure is admitted. A pipe 19 is connected with a reservoir or other source of fluid supply R and delivers 100 fluid under pressure to a suitable air inlet device comprising a valve casing 20 carried by a nipple 21 having a valve 22 slidably 105 therein and adapted to be actuated by a stem 23 which is connected to a lever 24 pivoted at 25 to a suitable fixed bracket. Means are provided for regulating the amount of air supply and also for shutting off the supply when the article has been delivered from the pipe 13. 110

The means comprises a chamber or casing 27 which opens into the receptacle and is

provided with a piston 28 connected by a piston rod 29 with the lever 24. The ball 30 forms a convenient and simple rocking connection between the piston and the piston rod. The spring 31 yieldingly holds the piston normally down, and the spring may be adjusted, and consequently the opening of the valve may be regulated, as by a screw 32 against which the spring abuts through 10 the medium of the backing plate 33.

With the parts disposed as in Fig. 5, the receptacle is open and the air is shut off. The operator at the forge drops a rivet through the opening 16 and the rivet drops 15 to the position at 14 in Fig. 1. The swinging handle 24 is then pushed down, which opens the valve 22 and air under pressure from the pipe 19 enters the receptacle and slams the door 17 shut and the air under 20 pressure then pushes the rivet through the delivery pipe. When the valve 22 was opened the piston 28 was pulled up to compress the spring 31 and the piston is held up by air pressure within the receptacle as soon as 25 the door 17 is shut.

When the rivet emerges from the pipe 13 this channel is open for air under pressure and this causes such a reduction of pressure within the receptacle that the spring 31 pushes the piston 29 down, and consequently the lever 24, and this in turn shuts the valve 22. The air is now entirely shut off. The door 17 is also open, since it drops down 30 when the air pressure is released by the emerging of the rivet from the delivery pipe, and is a signal to the operator at the forge that the rivet is delivered and another 35 can be deposited in the receptacle.

A failure of the door to open shows that 40 there is a stoppage in the pipe and thus prevents the placing of more than one rivet in the pipe.

The signal illustrated in Figs. 1 and 2 is 45 an audible one and comprises a whistle 34 secured to a flange 35 of a valve casing 36. A vertical port 37 is formed in the valve casing and is adapted to be normally closed by a piston 38 which is slidable within a chamber 39 formed in said casing. The piston 39 is normally held against a stop 41 50 in the position shown in Fig. 2, by means of a light spring 40. This piston is formed with a restricted passage 42 which permits the fluid from the pipe 19 to flow through 55 a pipe 43 and into the pipes P^3 , P and P^1 . When the pressure in these pipes is reduced by opening either of the vent valves V or V^1 , the piston 38 will be moved to the right, as in Fig. 2, against the action of the 60 spring 40 and thus permit the fluid to escape through the port 37 and sound the whistle or operate any other suitable sort of signal as may be desired.

The vent valves V and V^1 may be of any 65 suitable design and if desirable may be ar-

ranged to give an alarm when the pressure in the pipes P or P^1 exceeds a predetermined point. I have illustrated in Fig. 4, however, a valve adapted to be manually operated so as to vent pressure and cause 70 the actuation of the signal. The valve illustrated in Fig. 4 comprises a casing 44 having a spring pressed plunger 45 therein which is formed with a port 46 normally held out of alignment with passages 47 and 48 of the valve casing. By depressing the button 49 the port 46 can be brought into alignment with the ports 47 and 48 and thus vent 75 the pressure in the pipe P or P^1 to atmosphere and cause a signal to be given. 80

In Fig. 3 I have illustrated an alternative form of audible signal comprising a bell 50 carried by a suitable supporting arm 51 secured to the valve casing 36^a. A plunger 52 is slidably mounted in a chamber 37^a formed in the valve casing. This plunger is adapted to be lifted by air pressure against the action of a spring 53 when the piston 38 is moved to the right. The plunger 52 is connected with a reciprocating rod having rack 85 teeth 54 thereon which engage a ratchet 55 to which is suitably secured a plurality of strikers 56. It is apparent that when the plunger 52 is lifted the strikers will rotate 90 and cause the bell to ring, and that the spring 53 will restore the bar to normal position after each operation. 95

From the foregoing it will be understood that an operator at either of the receiving 100 stations B or C can by actuation of the vent valve V or V^1 cause the signal S to operate. A prearranged code can be used so that the operators at the receiving station can signal, for example, that the rivets are coming 105 either too slowly or too rapidly or that rivets of different sizes or different kinds, such as round head or countersink head rivets are desired.

I may employ one signal S at a sending 110 station which is provided with a multiplicity of delivery units 10 or I may provide separate signals for each delivery unit, each signal having individual characteristics of its own so as to enable the sender to identify 115 a signal with an operator in a given location.

Though I have described with great particularity of detail the construction of the apparatus herein shown it is not to be construed that I am limited thereto as changes 120 may be made by those skilled in the art without departing from the invention as defined in the appended claims.

What I claim is:

1. An apparatus of the class described including a fluid supply, a valve casing connected thereto, a signal whistle connected to said valve casing, a movable piston in said valve casing to control the operation of 125 said whistle and a manually operated vent 130

- valve located at point remote from the signal whistle and adapted to be operated to reduce the pressure on one side of said piston to cause a signal to be given by said 5 whistle.
2. An apparatus of the class described including a fluid supply, a valve casing connected thereto, a whistle connected to said valve casing, a movable piston arranged to 10 normally prevent the escape of fluid from said supply through said whistle and a manually operated vent valve located at a point remote from said whistle adapted to reduce the pressure on one side of said piston to permit the movement thereof and 15 cause the whistle to be sounded.
3. In combination a delivery apparatus and a signal apparatus including a fluid pressure supply, a receptacle having a de- 20 liver pipe to receive and transmit an article, an air inlet valve connected to said supply, means for opening the valve, retaining means operable by pressure from within the receptacle for holding the valve 25 open, and a door on the receptacle normally
- open and closed by pressure from within the receptacle, a signal operatively connected to said fluid pressure supply located in juxtaposition to said receptacle and means located at a remote point for manually controlling the operation of said signal. 30
4. In combination a delivery apparatus and a signal apparatus including a receptacle having a delivery pipe to receive and transmit an article, an air inlet valve, means 35 for opening the valve, retaining means operable by pressure from within the receptacle for holding the valve open, and a door on the receptacle normally open and closed by pressure from within the receptacle, a fluid 40 supply connected to said valve, a signal located in juxtaposition to said receptacle, a valve connected to said fluid supply and having a movable piston therein to control the operation of said signal and means for 45 reducing the pressure on one side of said piston to cause a signal to be given.

In witness whereof, I have hereunto signed my name.

JOHN G. HARROLD.
